(57) **CLAIM**

I claim the ornamental design for a metal card, as shown.

DESCRIPTION

FIG. 1 is a top perspective view of a metal card according to my new design.

FIG. 2 is a bottom perspective view from below the metal card.

FIG. 3 is a top plan view thereof.

FIG. 4 is a bottom plan view thereof.

FIG. 5 is a front elevation view thereof.

FIG. 6 is a rear elevation view thereof.

FIG. 7 is a left side elevation view thereof; and,
FIG. 8 is a right side elevation view thereof.
